UNITED STATES PATENT OFFICE.

PHILIP SIMPSON, OF NEW YORK, N. Y.

SEMI-INDIRECT-LIGHT ATTACHMENT.

1,194,083.

Specification of Letters Patent. Patented Aug. 8, 1916.

Application filed May 24, 1915. Serial No. 29,989.

To all whom it may concern:

Be it known that I, PHILIP SIMPSON, a citizen of the United States, and a resident of New York city, borough of Manhattan, 5 in the county and State of New York, have invented a new and Improved Semi-Indirect-Light Attachment, of which the following is a full, clear, and exact description.

My invention relates to semi-indirect 10 lights, and has reference more particularly to an attachment whereby an ordinary light fixture can be easily and quickly transformed into a semi-indirect light fixture.

An object of my invention is to provide 15 an attachment which is simple and inexpensive and which will utilize a shade of the present ordinary fixture for obtaining the semi-indirect light effect.

A further object of the invention is to 20 provide an attachment of the class described in which the lamp socket of the fixture is utilized for supporting the attachment.

With the above and other objects in view, 25 the nature of which will more fully appear as the description proceeds, the invention consists in the novel construction, combination and arrangement of parts as herein fully described, illustrated and claimed.

In the accompanying drawings, forming 30 part of the application, similar characters of reference indicate corresponding parts in both views.

Figure 1 is a vertical section through an ordinary suspension transformed into a 35 semi-indirect light by means of my attachment; and Fig. 2 is a modified reflector which can be utilized in connection with my attachment.

Referring to the drawings, 3 represents a 40 reflector of any suitable shape and size which has a central opening 4 through which a lamp 5 can project to engage a socket 6. The edge of the reflector at the opening is flared to form an exterior neck engageable 45 by screws 7 of the shade-holder 8 carried by the socket 6. Or any other means may be used for securing the reflector to the socket, if no shade-holder is provided thereon. The screws 7, which normally support a shade 50 9, are caused to disengage the shade, the lamp 5 being removed from the socket; the reflector 3 can then be engaged or connected to the shade support 8, as shown in Fig. 1.

Mounted adjustably within the reflector 3 55 is a suspension 10 consisting of a U-shaped member the threaded ends 11 of which pro-

ject through the reflector as shown. Nuts 12 and 13 are provided on the threaded ends whereby the length of the suspension below the reflector can be varied. The U-shaped 50 suspension 10, at the bottom thereof, has a cup 14 which is co-axial with the reflector, and which cup has a downwardly extended threaded stem 15. Engaging the threaded stem 15 is a retaining cup 16 adapted to 55 encompass the cup 14. The neck of the shade 9 is adapted to fit between the cup 14 and the retaining cup 16 when said shade is placed on the suspension 10. The shade is retained on the suspension by means of a 60 nut 17 threaded on to the stem 15, which clamps the retaining cup 16 and, therefore, the shade, to the suspension 10.

It will be noted that the shade 9 which has been removed from the shade support 8 65 may be utilized on my attachment as stated, therefore the only new members in my semi-indirect light attachment are the reflector 3 and the suspension.

My attachment can be secured to a light 70 fixture whether rigid or flexible, that is, one which is secured direct to the ceiling or one which is suspended from the ceiling by a wire, as the attachment is securable to the shade support carried by the socket. The 75 transformation does not require any special skill, as the only part to be removed is the shade, which can then be attached to the suspension 10 before the suspension is secured to the reflector. After the reflector is 80 attached to the shade support on the socket, the suspension with the shade can be secured to the reflector, after the lamp 5 has been secured to the socket. Thus, an ordinary 85 light fixture can be quickly and easily transformed into a semi-indirect light by means of my attachment.

In Fig. 2 a reflector 3' is shown which is of a different form than that in Fig. 1. It is self-evident that various forms of reflectors can be used in connection with my 90 attachment.

While I have described the principle of operation, together with the device which I now consider to be the best embodiment 105 thereof, I desire to have it understood that the device shown is merely illustrative and that such changes may be made as are within the scope of the appended claims.

I claim:

1. In combination with an incandescent lamp socket, a shade holder, a reflector de-

tachably supported by the holder, a translucent shade, a U-shaped suspension supported by the reflector, and means for securing the shade to the suspension to maintain the shade opposite the reflector.

2. In combination with an incandescent lamp socket, a shade holder, a reflector detachably supported by the holder, a translucent shade, a U-shaped suspension the ends 10 of which project through the reflector, means adjustable on the ends of the U securing the

same to the reflector, and means for securing the shade to the suspension so that the shade is opposite the reflector.

In testimony whereof I have signed my 15 name to this specification in the presence of two subscribing witnesses.

PHILIP SIMPSON.
